GRADE DETERMINING APPARATUS

Edward H. Canan, McKeesport, Pa.

Application March 14, 1933, Serial No. 660,619

12 Claims. (Cl. 33—174)

This invention relates to an apparatus for use in constructing and improving roads, and more particularly to an apparatus for readily proving the subgrade and finish grade of the road.

5 One object is to provide an apparatus for use in road building whereby it will be possible to readily secure a perfect and true riding surface.

Another object is to provide an apparatus for use in securing the sub and finish grades in road 10 construction work, which is readily adaptable to use under any conditions and does not require a track prelaid to grade or to a certain height above grade.

A further object is to provide an apparatus for 15 use in road building in which the crown boards or straight edges are mounted in a table suspended in a frame or carriage in such a manner that they may be readily made to conform to the desired grade line or elevation of the road, regardless of whether the frame or carriage of the apparatus is level or out of plumb.

A still further object is to provide an apparatus for use in road building which is simple in construction, easy to operate and handle, and does 20 not require any specially built track or the like.

These and other objects which will be herein-after made apparent to those skilled in this particular art are accomplished by means of this 25 invention, one embodiment of which is described 30 in the following specification and illustrated in the accompanying drawings, wherein:

Figure 1 is a plan view of an apparatus embodying my invention;

Fig. 2 is an end view of the apparatus illustrated in Fig. 1;

Fig. 3 is a section taken on line III—III of Fig. 1;

Fig. 4 is a section taken on line IV—IV of Fig. 1;

40 Fig. 5 is a plan view partially broken away, illustrating the means for maintaining the edging table in proper relation to the frame of the apparatus;

Fig. 6 is a plan view of an apparatus embodying a modification of my invention;

Fig. 7 is a sectional view taken on line VII—VII of Fig. 6;

Fig. 8 is an enlarged view of a bucket adapted to be used with my apparatus;

50 Fig. 9 is a partial view in side elevation illustrating the construction of the straight edge members; and

Fig. 10 is a section taken on line X—X of Fig. 9.

55 In the drawings, I have illustrated an appa-

ratus, embodying my invention, which is adapted to be used in road building where a subgrade and finished grade are desired to secure a true and perfect riding surface. In the construction or building of roads it is customary to grade the land over which the road is being built and form a base for receiving the paving or improving material, such as crushed stone, concrete or the like.

To secure a road which will stand up under heavy traffic and which will have a smooth even surface, it is important that not only the surface of the paving material be free from waves caused by high and low spots, but also that the paving material be of a uniform thickness. As a result, the base must be fairly close to grade to secure such thickness of the paving material and the surface of that material must be to grade to secure a smooth even, riding surface.

My improved apparatus for readily securing both the subgrade and the finish grade in road building, comprises a frame or carriage 10 which is mounted on flanged wheels 11 adapted to roll along a track 12. The track 12 which may be formed of wood or any other suitable material, is made in sections which are adapted to be laid down on the rough and irregular grade of the shoulders on each side of the road bed, so that as soon as the frame or carriage 10 is pushed from one section of the tracks to another, the sections vacated may be carried forward and laid down at the opposite end of the section on which the wheels of the frame then rests.

To grade or prove the crown of the road, the frame or carriage 10 has a table 13 mounted therein which comprises a pair of channel members 13' on which crown boards or straight edges 14 are assembled. So that the crown boards and edging table 13 will conform to the desired subgrade or finish grade, regardless of the irregularities of the grade of the track 12 and consequently of the frame or carriage 10, I mount the table in the frame in such a way that each corner thereof is capable of being raised and lowered relative to the frame to position the lower edges of the crown boards or straight edges 14 at the desired grade.

To secure such relative movement between the table 13 and the frame or carriage 10, each corner of the table has a member 15 secured thereto which is provided with a threaded bore to receive a screw 16 revolubly supported in a casting 16' secured to the frame of carriage 10. The screw 16 is so mounted in the casting 16' that it is free to tilt relative to the frame or carriage. To hold

the table 13 in proper position within the frame 10 a set of guides 17 are provided, one of each set being secured to the table 13 and the other to the frame or carriage 10, which keep the table 5 in vertical line therein.

From this construction it is apparent that the table 13 is supported at only four points within the frame or carriage and as a result by raising or lowering the corners of the table, the straight 10 edges or crown boards 14 may be readily made to conform to the desired grade even though the frame 10 of the apparatus is not level or is out of plumb.

So that the crown boards or straight edges 14 15 which extend longitudinally of the road may be adjusted to conform to the desired crown of the road, the ends of the crown boards or straight edges are adjustably mounted in the channels 13'. To move the crown boards or straight edges relative 20 to the members 13' screws 18 are provided which extend through the webs of the channel members and through threaded extensions 19 formed on the ends of the crown boards or straight edges. By regulating the screws 18, the crown 25 boards or straight edges 14 may be set so that the bottoms thereof define any desired crown of road.

In order that the adjustment needed to make the straight edges or crown boards 14 in the table 13 conform to the desired subgrade or finish 30 grade, targets 20 are swingingly mounted on the table 13. These targets are adapted to swing out over the frame or carriage 10 over a chalk line, designated as 21, which has been previously strung along the side of the road by the engineer and 35 denotes the finished grade lines, or elevations. When the targets 20 are swung over the chalk lines 21 each of the screws 16 is operated and the corners of the table 13 raised or lowered until the targets are just above the chalk line.

40 In operating my apparatus, the crown boards or the straight edges 14 are first adjusted in the table 13 so that the bottoms thereof conform to the desired crown of the subbase or finished road. That is to say, the crown boards or straight edges 45 14 are so adjusted that the bottom edges are in the same plane if a flat crown is desired, or define a concave surface when a rounded crown is contemplated. After the crown boards or straight edges 14 have been set, the operator pushes the apparatus along the track 12 over a section of the road to be graded.

The targets 20 are then swung over the chalk line 21 denoting the grade and each of the screws 55 16 adjusted until the corners of the table 13 have been raised or lowered to place the targets in a position where they just clear the chalk line. In such position the bottoms of the crown boards or straight edges then define the proper grade.

The operator then has a clear view of the pavement or subgrade covered by the apparatus for a space the full width of the road and the full length of the crown or edging boards 14 and can quickly see any irregularities therein. If any low 60 or high spots appear at any place along the length of the crown or edge boards 14, the operator, if the grade is high, shovels out the surplus material and tosses it into a bucket 22 carried on a shelf 23 mounted on the frame or carriage, or if the grade is low the reverse operation is performed 65 and the proper grade is therefore readily secured.

These buckets 22 are constructed with a high back 24 so that superfluous material may be readily thrown thereinto from any point within the confines of the table 13.

70 75 In Figs. 6 and 7, I have shown a modified form

of my apparatus in which the crown boards extend transversely of the road instead of longitudinally.

This modified structure of my apparatus comprises a frame or carriage 30 which is mounted on rollers 31 adapted to travel on a track similar in construction to the track heretofore described and adapted to be laid in a like manner. Mounted within the frame or carriage 30 is a table 33, the longitudinal edges of which are in 10 the form of a channel to provide a trolley track 34 for receiving trolleys 35 carrying crown boards 36. The corners of the table 33 are adjustably mounted in the frame or carriage 30 by means of screws 37 whereby each corner of the table 15 may be raised or lowered relative to the frame to place the bottom of the crown boards 36 at the proper or desired grade.

In the use of this structure the frame or carriage 30 is pushed over a section of the road 20 to be graded and the table 33 which carries targets similar to those in the previous modification, is then set to secure the grade regardless of whether the frame or carriage is level or out of plumb. The operator then moves the crown 25 boards 36 back and forth in the track 34 and removes or fills in the high or low places, respectively, until the proper grade is secured.

It is to be understood that either modification 30 of my apparatus may be used to secure both the 35 subgrade and the finish grade on the road, or one may be used to secure the base grade and the other may be used to secure the finish grade, or the two structures may be combined into one structure by connecting the channel members 35 of the modification illustrated in Fig. 1 with the trolley track side members 34 of the table 33. In such a combination, longitudinally extending straight edges 14 would be removed when it was desired to use the transverse crown boards, 40 and the trolleys 35 carrying the crown boards 36 would be mounted in the track 34.

The straight edges 14 and the crown boards 36 which may be formed in any suitable way and of any suitable material are preferably made from 45 a steel beam having a wooden shoe along the bottom thereof. Since the only difference of construction between the straight edges and the crown boards is that the lower surface of the latter is curved to correspond to the crown of the 50 road only the construction of one of the straight edges will be described. As shown in Figs. 9 and 10 my preferred straight edge 14 comprises a lattice work beam 40 of substantially I-shape in section having a wooden shoe 41 secured to 55 the bottom flange thereof. In order that the shoe 41 may be maintained as a perfect straight edge regardless of the shape of the beam 40 caused by the expansion and contraction or the like thereof the lower flange of the beam 40 is provided 60 with transverse slots 42 through which bolts 43 extend for securing the shoe to the flange. The heads of the bolts 43 are countersunk in the lower face of the shoe 41 to present a smooth flat surface on the bottom of the shoe. When the 65 shape of the beam has been changed due to any cause the shoe may be readily adjusted to maintain a true straight edge by loosening the bolts 43 and moving them in the proper direction in the slots 42 until the side of the shoe is again 70 in a straight line. To readily unfasten the shoe from the flange of the beam 40 the bolts 43 are threaded through washers 44 on the opposite side of the flange therefrom and are provided with thumb knobs 45, thereby making it possible to 75

readily loosen the bolts 43 and make the necessary adjustments in the shoe 41.

It is readily apparent that I have provided an apparatus for use in road construction which does not require a level track or a track which has been brought to grade in order to secure a perfect surface since each corner of the table carrying the crown or straight edge boards is movable relative to the frame or carriage of the apparatus and as a result the straight edge or crown boards may be readily set at the desired grade although the frame or carriage is not level or is out of plumb due to the track being placed on rough or irregular shoulders at each side of the road.

While I have described a preferred embodiment of my apparatus as having a straight edge table movable relative to the frame so that the crown boards carried thereby may be readily adjusted to the desired grade of the road, it is understood that the edging table may be rigidly secured to the frame or carriage and the frame or carriage mounted on the wheels in such a manner that it is adjustable relative thereto, whereby the frame or carriage carrying the straight edges and crown boards may be raised and lowered relative to the wheels to position the straight edges and crown boards to the desired grade regardless of the relation of the wheels to that grade. That is to say, the screw members shown in my preferred embodiments may be attached to the frame and the axles of the apparatus so that the whole frame or carriage may be adjusted relative to the wheels.

While I have described one embodiment of my invention, it is to be understood that certain modifications, changes, and substitutions may be made without departing from the spirit of my invention or the scope of the appended claims.

What I claim as new and desire to secure by Letters Patent is:

1. An apparatus of the character described comprising a frame, an edging table, and separate means for supporting each corner of said table in said frame, each of said means being independently adjustable, whereby the table can be raised and lowered relative to said frame and made to conform to grade line of the road regardless of the position of the frame.

2. An apparatus of the character described comprising a carriage, a table supported by said carriage and having a series of edging members therein, and means for attaching the corners of the table to said carriage.

3. An apparatus of the character described comprising a frame, an edging table mounted in said frame, crown boards slidably mounted in said table, and means for raising and lowering said table relative to said frame.

4. An apparatus of the character described comprising a frame, channel members supported on said frame, edging members carried by said channel members, said channel and edging members forming an edging table, separate means for raising and lowering each corner of said table relative to said frame, and guide means for holding said table in position within said frame.

5. An apparatus of the character described comprising a frame, a table supported at its corners in said frame, edging members mounted on said table, means for raising and lowering the ends of said edging members relative to said table, and individual means for moving each corner of said table relative to the frame to place said edging members in position to conform to the grade of the road regardless of the relation of the frame to said grade.

6. An apparatus of the character described comprising a frame, a table, screw supporting means at the corners of the table and frame, straight edge members mounted on said table and means for holding said table in vertical position within said frame.

7. An apparatus of the character described comprising a frame, a table within said frame, means for individually and adjustably supporting each corner of said table in said frame, and crown boards movable longitudinally within said table.

8. An apparatus of the character described comprising a frame, a table within said frame and supported at the corners thereof, means for individually raising and lowering each corner of said table relative to said frame, means for holding said table in position relative to said frame, edging members mounted on said table and means for moving the ends of said edging members relative to said table.

9. An apparatus of the character described comprising a frame, a table within said frame and supported at the corners thereof, crown boards carried by said table, means for raising and lowering each corner of the table relative to the frame to position said crown boards to the desired grade, means for holding the table in position within said frame, and means for readily determining the amount of raising or lowering necessary to make each corner of the table conform to the desired grade.

10. An apparatus for use in road grading comprising a carriage, a table mounted on said carriage, a series of edging members movably mounted in said table, means for moving said edging members relative to said table and screw means for raising and lowering said table relative to said carriage to place said edging members in position to conform to the desired grade.

11. An apparatus for use in grading of roads comprising a wheeled carriage, a table supported by said carriage, edging members carried by said table, separate means for changing the position of each corner of said table relative to the wheels whereby the edging members can be readily adjusted to grade.

12. An apparatus of the character described comprising a substantially rectangular hollow, wheeled carriage, a table, means for independently and adjustably securing each corner of said table to said carriage, edging members and means for adjustably securing the ends of said edging members to said table.

EDWARD H. CANON.
